UNITED STATES PATENT OFFICE

2,497,701

SMOOTHING PLANE

Sam Telasky, Bloomville, N. Y., assignor of fifty
per cent to Clifford H. Telasky, Bloomville,
N. Y.

Application August 15, 1946, Serial No. 690,686

1 Claim. (Cl. 145—5)

1

This invention relates to new and useful improvements and structural refinements in smoothing planes, and the principal object of the invention is to provide a device of the character herein described, such as may be conveniently and effectively employed for preventing the shavings from accumulating and obstructing the chip passage in the vicinity of the cutting knife, as is frequently experienced when using planes of conventional design.

A further object of the invention is to provide a device for guiding the chips or shavings, which is self functioning in operation and which may be applied to both new planes, or alternatively, as an attachment for planes already in existence.

Another object of the invention is to provide a chip guiding device which is simple in construction and operation.

An additional object of the invention is to provide a chip guiding device which may be readily disassembled for purposes of inspection or repair.

With the above more important objects in view, and such other objects as may become apparent as this specification proceeds, the invention consists essentially of the arrangement and construction of parts as illustrated in the accompanying drawings, in which:

Figure 1 is a side elevation of a smoothing plane, showing the invention in situ therein

Figure 2 is a top-plan view of the same

Figure 3 is a cross-sectional view, taken substantially in the plane of the line 3—3 in Figure 2, and

Figure 4 is a cross-sectional view, taken substantially in the plane of the line 4—4 in Figure 3.

Like characters of reference are used to designate like parts in the specification and throughout the several views.

Referring now to the accompanying drawings in detail, the invention consists of a chip guiding device designated generally by the reference character 5 and may be used in association with a smoothing plane 6 of more or less conventional design. This plane customarily includes in its construction a substantially U-shaped, channel-like base 7 formed with a chip passage 8 and provided with a suitable cutting knife 9. The cutting edge portion of this knife extends into the passage 8, as will be clearly understood.

The essence of the invention resides in the provision of the chip guiding device 5, as aforesaid, the same embodying in its construction a pin 10 secured in suitable apertures 11, 12 formed in the sides 13 of the base 7. One of these aper-

tures (12) is screw-threaded to receive a threaded portion 14 formed at one end of the pin, the remaining end of the pin being provided with a diametrically extending kerf 15. It will be noted that in this manner, the pin 10 may be firmly and securely mounted in the base 7.

It will be also observed that the pin extends transversely of the passage 8 forwardly of the knife 9 and a roller 16 is rotatably positioned 10 on the pin, as is best shown in Figure 3. The roller 16 extends nearly the full width of the passage 8 and the underside of the roller is substantially flush with the under-surface 16 of the base 7.

15 An upright web 17 is provided, preferably by integral formation, between the sides 13 of the base 7, and a deflector block 18 is secured to the web 17 by means of a plurality of suitable screws 19. The block 18 is configurated substantially as shown and extends substantially the full length 20 of the roller 16.

It will be noted that the deflector block 18 is disposed adjacent the roller 16 and that a surface 20 thereof is concaved complementarily to the lateral surface of the roller, as is best shown 25 in Figure 3.

When the invention is placed in use, the plane 6 is manipulated in the well-known manner and the chips or shavings originating at the cutting edge of the knife 9 will be guided upwardly by the roller 16 and deflected by the block 18, so that they will not accumulate and obstruct the passage 8.

It is believed that the advantages and use of 35 the invention will be clearly understood from the foregoing disclosure, and accordingly, further description thereof at this point is considered necessary.

While in the foregoing there has been shown 40 and described the preferred embodiment of this invention it is to be understood that minor changes in the details of construction, combination and arrangement of parts may be resorted to without departing from the spirit and scope 45 of the invention as claimed.

What I claim as my invention is:

In a smoothing plane including a body portion 50 comprising a flat base and perpendicular side walls, said base having a transverse chip receiving opening, a forwardly and downwardly inclined blade secured to said body portion and having its cutting edge positioned in said opening and a perpendicular wall rising from said base disposed forwardly of said opening; a chip 55 guiding device mounted on said body portion and

comprising a transversely extending pin detachably secured to the sides of said body portion, a roller mounted on said pin and received in said opening, the surface of the roller being substantially flush with the outer surface of the base, an elongated substantially triangular block detachably secured to said perpendicular wall, said block having a concaved recess provided in one face thereof, the wall of said recess embracing a part of the cylindrical surface of said roller, said 10 recess extending throughout the length of said roller.

SAM TELASKY.
